UNITED STATES PATENT OFFICE.

JOHN A. DUGGAN, OF BATTLE CREEK, MICHIGAN.

SANITARY TOOTHBRUSH-HOLDER.

1,370,793.

Specification of Letters Patent.

Patented Mar. 8, 1921.

Application filed December 16, 1919. Serial No. 345,436.

To all whom it may concern:

Be it known that I, JOHN A. DUGGAN, a citizen of the United States, residing at Battle Creek, in the county of Calhoun and 5 State of Michigan, have invented certain new and useful Improvements in Sanitary Toothbrush-Holders, of which the following description, taken in connection with the appended claim and accompanying drawing, 10 forms a specification.

The invention relates to sanitary tooth brush holders and more particularly relates to means for hinging the sanitary brush covers.

15 The present invention very particularly relates to that class of tooth brush holders in which ventilated, transparent covers for the brush are employed, the same being suspended on curved wire hinges operative at 20 the ends of arms struck up from a framework or backing, and resting on spring prongs between which the brush is supported, said prongs also being struck up from said framework.

25 A characteristic feature of the present invention lies in an offset in the hinge-wire that supports the brush cover.

An important object is to so form the 30 curved hinge supports for the brush covers that no difficulty will be experienced in assembling the parts.

In the manufacture of glass utensils it has been found that more or less non uniformity exists in the finished product and is 35 a source of trouble in placing fittings, especially when the fittings are formed with exactness and for predetermined sizes of perfect uniformity. With the object in view of overcoming this difficulty by forming 40 a hinge member capable of being readily fitted to either a uniform or non uniform surface, my invention consists in the novel construction and manner of attachment of said hinge member to tooth brush holders 45 of the character set forth, and will herein-after be more fully explained, illustrated in the accompanying drawing and defined in the appended claim.

In the drawing forming a part of this 50 specification, Figure 1 is a front elevation of a sanitary tooth brush holder comprising three covers, the one to the left containing a tooth brush, the center one tilted outwardly in the manner of receiving a brush, 55 and the one to the right fully closed.

Fig. 2 is a plan view of the same, excepting the brush.

Fig. 3 is a side view of a tooth brush holder, the dotted lines showing a cover partially tilted to receive a brush. 60

Fig. 4 is a detail plan view of a metallic spring clip or cover hinge.

Like marks of reference refer to corresponding or equivalent parts in the different views, in which A represents a framework 65 or backing of non corrosive composite material similar to vulcanite celluloid etc. having struck up outwardly-extending ears 1 and seating prongs 2, the former being perforated at their extremities to form eyelets for 70 spring clip hinges 3, the latter forming seating shoulders for a tooth brush, as B, and also resilient seats for glass tooth brush covers, as C.

The tooth brush holder may be attached 75 to a wall, frame or casement, by means of screws, nails or the like, placed through apertures, as 4, through the flattened portion of the frame A.

In the drawings I have shown a series of 80 three tooth brush holders in one frame. It would be obvious, however, that either one or more could be employed, the drawing as made being in triplicate to more clearly show the method of its construction and 85 operation.

The tooth brush holders C are of transparent material; glass, for instance—open at one end and having a rounded opposite or top end, and through the upper wall of 90 which a ventilating hole may be formed. These holders are secured between the outwardly extending ears 1 by means of semi circular shaped bands 5 and the spring clips 3 aforesaid, and when in operative position 95 rest with their open ends on the supporting brush prongs 2, the prongs being curved downwardly at their extremities to readily permit said covers to swing thereover yet slightly impinge them when tilted from a 100 vertical position.

The bands 5 are preferably made of a material similar to the frame back A, and at their ends are perforated to receive the outwardly-curved ends of the spring hinge 105 clips 3, with which an encircling resilient band is formed for supporting a brush cover.

A spring hinge clip 3 as shown is a semi circular piece of wire bent outwardly or sidewise centrally between its slightly re- 110

versed curved ends 6 and forms an offset bow 7, the object of the offset being to permit said clip to slightly give or take in its attachment with a band 5 in encircling a brush cover C, as hereinafter set forth.

In operation, a band 5 is placed on a cover C at or near its point of suspension between a pair of ears 1 and a clip 3 placed diametrically opposite, the ends of the latter projecting through the apertures in the ends of the former, the ends of said clip thrust through apertures in the ends of said ears.

A clip, as 3, by the provision of the offset curve 7 affords sufficient resiliency to permit the interlocking of the band 5 without difficulty and the subsequent assembling of the extremities of said clip through the supporting ears 1.

From the foregoing description, taken in connection with the accompanying drawing, a more extended explanation of the construction and operation of my improved tooth brush holder is believed to be unnecessary.

Having, therefore, set forth the objects

and advantages of my invention, what I claim as new and desire to secure by Letters Patent, is:—

In a device of the class set forth, the combination with a framework having spaced outwardly-extending ears with apertures through their outer extremities, a cylindrical tooth brush cover adapted to swing between said ears, and a flattened semi circular band having apertures near its ends fitted to the forward side of said cover and a semi circular shaped metallic clip fitted to the opposite side of said cover and having an offset centrally between its ends, said clip having offset ends extending through the apertures at the ends of said band and through the apertures near the ends of said ears, said clip and said band forming a suspending bond swiveled to and between said ears, substantially as and for the purpose set forth.

JOHN A. DUGGAN.
